SCRAPER

Charles Le Bleu, Los Angeles, Calif.

Application March 5, 1940, Serial No. 322,303

17 Claims. (Cl. 37—126)

This invention relates generally to material digging, scraping, leveling, grading and transporting machines, and more specifically to that class of machines commonly known as scrapers, and is an improvement upon my co-pending application Serial No. 200,919 filed April 8, 1938, which issued as Patent No. 2,223,829 dated December 3, 1940.

In my co-pending application above noted, I disclose and describe a scraper including a bowl support having a bowl swingably mounted thereon and means for raising and lowering said bowl support substantially without tilting it, said raising and lowering means comprising operably associated front and rear frames pivotally connected with said support, and means for swinging said frames. The advantage of this structure resides in the fact that the bowl bottom may be disposed in a substantially horizontal plane in both loading and carrying positions thereof.

It is therefore, the principal object of this present invention to improve upon the disclosures in my co-pending application Serial No. 200,919, which issued as Patent No. 2,223,829 dated December 3, 1940, by simplifying the same so as to provide a less expensive device and yet one which will be effective for the purpose for which it is designed.

More specifically, an object of this invention is the provision in a machine of the class named, of a main frame supported for tilting movement in a vertical plane, a bowl pivotally supported on said main frame and including a bottom, a secondary frame supported for tilting movement in a vertical plane and pivotally connected with said main frame, operable means between said main and secondary frames for swinging the same to raise and lower said bowl so as to selectively dispose the same in loading and carrying positions, and means between said secondary frame and said bowl arranged to function in response to the swinging movement of said secondary frame so as to swing said bowl about its pivotal connection with said main frame in a direction maintaining the bottom of said bowl in a substantially constant parallel relation to the ground thereunder in both loading and carrying positions of said bowl.

Other objects and advantages of this invention will be apparent to those skilled in the art upon a detailed perusal of these specifications and the attached drawings wherein I have exemplified and described my invention, but it is to be understood that my invention as herein exemplified and

described is susceptible to numerous changes and modifications in the co-relation and forming of the various parts, members and features, without departing from the spirit of the invention as defined in the annexed claims.

Figure 1 is a side view in elevation of my invention disposed in carrying position.

Figure 2 is a fragmentary top plan view of a portion of the invention showing the means by which the secondary frame acts upon the bowl for maintaining the bottom thereof in a substantially constant parallel relation to the ground thereunder, all parts being in the scraping position.

Figure 3 is a side elevation in section of my invention in loading position.

Figure 4 is a side elevation of a modified form of my invention in carrying position.

Figure 5 is a side elevation in section of the modified form of my invention, all parts thereof being disposed in loading position.

Referring now more specifically to structure by alluding to reference characters on the drawings, and for the time being, to Figures 1 to 3 inclusive, a main frame 10 includes transversely spaced side walls 11 to which are secured reinforcing frame members 12, secured at their forward ends to a transverse beam 13, and to which there is also secured a triangular frame member 14, the lower end 15 of triangular frame member 14 being articulately mounted as shown at 16, see Figure 3, upon a transversely disposed axle 17 having rolling supports 18 journaled thereon and is provided with a draft pole 19 adapted at its forward end, as shown in Figure 1, for connection to a draft device, and a transverse blade support 20 extends between sidewalls 11 and is supported thereon.

A blade 21 is detachably secured to blade support 20.

A transverse beam 22 is disposed at the lower rear ends of sidewalls 11 and is attached at its opposite ends thereto.

Thus it is seen that I have provided a main frame 10 supported on front axle 17 for swinging movement in a vertical plane.

A bowl 23 is disposed between sidewalls 11 and is supported for tilting movement about a pivot 24, bowl 23 including a bottom 25 and a back wall 26, provided at their opposite ends with end plates 27 rigid therewith.

A secondary frame 28 is disposed rearwardly of main frame 10 and comprises a transverse beam 29 provided at each of its ends with a forwardly extending arm 30 pivotally connected ad-

acent their front ends with frame 10 as shown at 31, beam 23 being provided with depending brackets 32 supported upon an axle 33 having rolling supports 34 journaled thereon. Thus I have provided a secondary frame 28 supported for swinging movement in a vertical plane and pivotally connected adjacent its forward end with main frame 10 adjacent its rear end, as shown at 31.

Transverse beam 22 is provided with brackets 35 supporting a horizontal pin 36 upon which is journaled sheave means 37, and transverse beam 29 is provided on its forward side with brackets 38 arranged relative to brackets 35 and supporting a horizontal pin 39 upon which is journaled sheave means 40. A flexible element 41 is anchored as shown at 42 and passes thence back and forth about sheave means 35 and 40, thence about direction change sheaves 43 which are journaled on pins 44 carried by cross beam 29, thence forwardly about a direction change sheave 45, see Figure 1, journaled in common with an arm 30 about pivot 31, and may extend thence to a winding drum (not shown because of conventional design).

Now it is readily seen that a pulling force may be applied to flexible member 41 to cause main frame 10 to swing upwardly at its rear end about axle 17 as a pivot and that blade 21 and bowl 23 may thus be raised, whereas a slackening of cable 41 will cause the blade and bowl to be lowered.

The opposite ends of bowl 23 are each provided with a detachable bracket 46 carrying a laterally projecting journal 47 upon which is journaled a roller 48, each of the journals 47 being arranged above an arm 30, each of which is provided with a portion 30' adapted to engage a roller 48 so that rollers 48 normally rest thereon, portion 30' being, in this instance, formed as a rigid integral part of arms 30, and it is readily seen that vertical movement of arms 30 about pivots 31 and relative to the main frame 10 must cause the bowl 23 to tilt relative to main frame 10 about pivot 24.

Brackets 46 are detachably secured to bowl 23 so that they may be selectively positioned and secured thereto to thus selectively determine the parallel relation of bowl bottom 25 relative to the ground thereunder. Soil conditions vary and while it is advantageous to dispose the bowl bottom as close to the ground as possible in loading position thereof, yet this is not always feasible in ground containing large rocks and the like, so that it may, under such conditions, be necessary to dispose the bowl bottom in a slight upward tilt at its rear end when in loading position.

Now having selectively secured brackets 46 to bowl 23, suitable manipulation of flexible element 41 may be resorted to for causing frames 10 and 23 to swing in a vertical plane and relative to each other for raising or lowering bowl 23, and since the rear end of bowl 23 is normally supported upon means 30' by means of the bracket, journal and roller assembly 46, 47 and 48 respectively, said swinging movement of frame 28, and consequently arms 30, will cause said bowl to be swung about pivot 24 in a direction maintaining said bowl bottom 25 in the selected parallel relation to the ground thereunder in both loading and carrying positions of said bowl.

A transverse beam 49 is secured along the upper edge of back wall 26 and is provided with upstanding brackets 50 carrying a horizontal pin 51 having sheave means 52 journaled thereon.

An auxiliary bowl 53 is disposed transversely of and in front of sidewalls 11 and is arranged relative to blade 21. Arms 54 are secured at their front ends to auxiliary bowl 53 and extend thence rearwardly to a pivotal connection with frame 10 as shown at 55. The auxiliary bowl 53 is thus arranged relative to sidewalls 11 and blade 21 so that it may serve to open or close the intake opening defined by sidewalls 11 and blade 21.

10 Auxiliary bowl 53 is provided with upstanding brackets 56 carrying a horizontal pin 57 having sheave means 58 journaled thereon.

Main frame 10 is provided with upstanding brackets 59 arranged relative to brackets 50 and 56 and supports a horizontal pin 60 having sheave means 61 journaled thereon.

20 A flexible element 62 is secured at an end to brackets 59 as shown at 63 and extends back and forth about sheave means 52 and 61, thence back and forth about sheave means 61 and 58, and may extend thence to a winding drum (not shown because of conventional design).

It will be readily understood that a pulling force may be applied to flexible element 62, and 25 as a result, auxiliary bowl 53 being lighter than main bowl 23, will move upwardly, and when the auxiliary bowl 53 has reached its uppermost limits of movement the main bowl 23 will then be caused to tilt about pivot 24 as an axis, whereas, 30 a slackening of flexible element 62 will permit the main bowl 23 to first, being heavier than auxiliary bowl 53, tilt downwardly at its rear end about pivot 24, and when rollers 48 have contacted arms 30, the auxiliary bowl may then 35 swing downwardly about pivots 55 to closed position.

In operation, my invention may be secured to a pulling device and drawn thereby across a surface to be treated. When it is desired to gather 40 a load of materials, suitable manipulation of flexible element 41 may be resorted to for lowering blade 21 into scraping contact with the ground, bowl 23 also moving downwardly with blade 21, and suitable manipulation of flexible element 62 45 is resorted to for swinging auxiliary bowl 53 upwardly to uncover the intake opening. It should be noted at this point, that as pivot 24 moves downwardly in response to suitable manipulation of cable 41 and the resulting downward swinging movement of frames 10 and 28, arms 30, as they swing about pivots 31 and relative to frame 10, will impart an upward tilting movement to bowl 23 relative to frame 10 so as to maintain bowl bottom 25 in the selected parallel relation 50 to the ground thereunder and thus cause bottom 25 to assume the most advantageous position for receiving the load scraped up by blade 21.

When the desired load has been accumulated, 55 cable 62 is slackened to allow auxiliary bowl 53 to move downwardly to closed position, and a pulling force is applied to cable 41 to raise the main and auxiliary bowls and dispose the machine in the carrying position of Figure 1, and in which position the machine may be drawn to the place where the load is to be discharged.

When it is desired to discharge the load, a pulling force is applied to cable 62 with the results that auxiliary bowl 53 swings to open position, and when the uppermost limits of movement thereof have been reached, main bowl 23 tilts upwardly about pivot 24 to such a degree that the materials therein may spill outwardly therefrom.

70 75 The bowls 23 and 53 may then again be dis-

posed in the position of Figure 1 by simply slackening cable 62.

Referring now to a modified form of my invention, shown in Figures 4 and 5, a main frame 65, comprises spaced apart sidewalls 66 rigidly connected at their rear end by transverse beams 67 and 68 having rearwardly extending frame portions 69 rigid therewith and provided with a transverse axle 70 upon which are journaled rolling supports 71. Sidewalls 66 are rigidly connected at their lower forward ends by means of a transverse blade support 72 extending between sidewalls 66 and rigidly attached at its opposite ends each to a sidewall 66, the upper forward portions of sidewalls 66 being cross connected by an overhead structure 74 comprising uprights 75 rigid with sidewalls 66 and connected at their upper ends by a transverse beam 76. Sidewalls 66 are further re-enforced by channel members 77 rigid therewith.

A transverse scraper blade 73 is detachably secured to blade support 72.

Thus, it is readily seen that I have provided a main frame 65 supported for tilting movement in a vertical plane about a rear pivot 70.

A bowl 78 is disposed between sidewalls 66 and is supported for tilting movement about a pivot 81. Bowl 78 including a bottom 79 and a back wall 80, provided at their opposite ends with side plates 82 rigid therewith, the upper edge of back wall 80 having a transverse beam 83 rigidly attached thereto and to side plates 82.

A secondary frame 84 includes arms 85 disposed one along each side of frame 65 and converging at their forward ends to a rigid connection with an upstanding arm 86 intermediate its ends, the lower end of upstanding arm 86 being articulately mounted, as shown in Figure 5, upon a transverse axle 87 having rolling supports 88 journaled thereon, axle 87 being adapted as shown for connection to a draft device.

The rear ends of arms 85 are each provided with a cross head 89 rigid therewith, the lower portion of cross head 89 being pivotally connected with main frame 65 for swinging movement relative thereto about pivot 81.

Thus, I have provided a secondary frame 84 supported for swinging movement in a vertical plane and pivotally connected adjacent its rear end with main frame 65 as shown at 81.

A horizontal pin 90 is supported by upstanding arm 86, adjacent the upper end thereof, and has sheave means 91 journaled thereon.

A thrust device 92 is provided with slots 93 through which pin 90 projects thus slidably supporting thrust device 92 upon arm 86, the rear end of thrust device 92 being pivotally connected at 94 with brackets 95 carried by the overhead structure 74.

A horizontal pin 96 is supported on the forward end of thrust device 92 and has sheave means 97 journaled thereon.

A cable 98 is anchored at 99, as shown, and passes thence back and forth about sheave means 91 and 97 and may extend thence to a winding drum (not shown because of conventional design).

As clearly shown in Figure 4, bowl 78 is provided at each side thereof with a laterally projecting journal 100 upon which is journaled a roller 101 arranged relative to the vertical portion 102 formed on the free end of a link 103, the forward end of horizontal portion 104 of link 103 being pivotally connected at 105 to the upper arm 106 of a cross head 89, cross head 89 being

rigid integral portion of the secondary frame 84 as hereinbefore explained, and the free end 102 of link 103 being freely supported, as shown, relative to roller 101, so that the secondary frame of the modified form of my invention is also adapted, by means comprising pivoted links 103, to engage rollers 101 and to swing bowl 78 relative to main frame 65 as said secondary frame swings about its pivotal mounting.

From the foregoing description it will be readily seen that a pulling force may be applied to cable 98 to pull sheave means 91 and 97 toward each other resulting in swinging upstanding arm 86 forwardly and consequently the rear ends of arms 85 upwardly while at the same time a force is applied rearwardly to overhead structure 74 in a direction extending above axle 70 thus tending to swing the forward end of frame 65 upwardly about the rear wheels 71 as an axis, with the results that bowl 78 together with blade 73 is raised, and it is clear that bowl 78 together with blade 73 may be lowered by slackening cable 98.

Now it is to be particularly noted that as arms 85 and cross head 89 swing relative to main frame 65 about pivot 81 in response to suitable manipulation of cable 98, the triangular links 103, contacting rollers 101, will be caused to move and impart a measure of tilting movement to bowl 78 about pivot 81 in a direction maintaining bowl bottom 79 in substantially a horizontal position in any tilted positions of frames 65 and 84, so that it may be said that bowl 78 may be raised and lowered substantially without tilting it.

An auxiliary bowl 107 is disposed transversely of and in front of side walls 66 and is arranged relative to blade 73. Arms 108 are secured at the front ends to the auxiliary bowl 107 and are pivotally connected at their rear ends with main frame 65 at 109. The auxiliary bowl 107 is thus arranged and supported relative to sidewalls 66 and blade 73 so that it may serve to open or close the intake opening defined by sidewalls 66 and blade 73.

Auxiliary bowl 107 is provided with brackets 110 supporting a horizontal pin 111 upon which is journaled sheave means 112.

Brackets 95 carried by overhead structure 74, are provided with a horizontal pin 113 upon which is journaled sheave means 114.

Cross beam 83, carried by back wall 80 of bowl 78, is provided with brackets 115 supporting a pin 116 upon which is journaled sheave means 117.

A cable 118 is anchored as shown at 116 and passes back and forth about sheave means 114 and 117, thence back and forth about sheave means 114 and 112 and may extend thence to a winding drum (not shown because of conventional design).

Now it will be readily understood that a pulling force may be applied to cable 118, and as a result, auxiliary bowl 107, being lighter than main bowl 78, will swing upwardly about pivots 109, and when the auxiliary bowl has reached its uppermost limits of movement the main bowl 78 will then be caused to tilt about pivot 81 as an axis, whereas a slackening of cable 118 will permit the main bowl 78 to tilt downwardly at its rear end about pivot 81, and when rollers 101 have contacted the vertical portion 102 of links 103, the auxiliary bowl 107 may then swing downwardly about pivots 109 to a closed position.

In operation, the modified form of my invention, Figures 4 and 5, may be secured to a pulling device and drawn across a surface to be treated.

When it is desired to gather a load of materials, suitable manipulation of cable 98 may be resorted to for lowering blade 73 into selected scraping contact with the ground, bowl 78 also moving downwardly with blade 73, and suitable manipulation of cable 118 is resorted to for swinging auxiliary bowl 107 upwardly to uncover the intake opening.

When the desired load has been accumulated, cable 118 may be slackened to allow auxiliary bowl 107 to swing downwardly about pivots 109 to close the intake opening and a pulling force is applied to cable 98 to raise the main and auxiliary bowls, together with blade 73, and dispose the device in the carrying position of Figure 4, and in which position the machine may be drawn to the place where the load is to be discharged.

When it is desired to discharge the load, a pulling force is applied to cable 118 with the results that auxiliary bowl 107 is caused to swing upwardly about pivots 109 to a position uncovering the intake opening and in which position materials may spill outwardly therefrom, and when auxiliary bowl 107 has been swung to its uppermost limits of movement, main bowl 78 will be caused to tilt upwardly about pivot 81 to a position spilling materials outwardly therefrom.

The bowls 78 and 107 may then again be disposed in either of the positions of Figures 4 and 5 by suitable manipulation of cables 98 and 107.

From the foregoing description, it will be seen that I have exemplified and described such a device as substantially fulfills the objects of my invention as set forth, and what I claim as new and useful and desire to secure by Letters Patent is:

1. In a machine of the character described, a main frame supported adjacent an end thereof for tilting movement in a vertical plane, a main bowl pivotally supported for vertical tilting movement concentrically about a horizontal pivot fixed on said main frame and including a bottom wall, a secondary frame supported adjacent an end thereof for tilting movement in a vertical plane, the free end of said secondary frame being arranged relative to the free end of said main frame and pivotally connected thereto, operable control means for tilting said main and secondary frames for raising and lowering said bowl so as to selectively dispose the same in a loading or a carrying position, and said secondary frame being arranged and adapted to act upon said bowl so as to swing the same about its pivotal mounting in a direction maintaining said bowl bottom in a substantially horizontal position during the tilting movement of said frames.

2. In a machine of the character described, a main frame supported adjacent an end thereof for tilting movement in a vertical plane, a main bowl including a bottom wall, horizontal pivot means supported in fixed position on said main frame and by which said bowl is pivotally connected directly thereto for vertical tilting movement about said pivot means as an axis, a secondary frame supported adjacent an end thereof for tilting movement in a vertical plane, the free end of said secondary frame being arranged relative to the free end of said main frame and pivotally connected thereto, operable control means for tilting said main and secondary frames for raising and lowering said bowl so as to selectively dispose the same in a loading or a carrying position, and means between said secondary frame and said bowl arranged to function in re-

sponse to the tilting movement of said secondary frame so as to swing said bowl about its pivotal mounting in a direction maintaining said bowl bottom in a substantially horizontal position during the tilting movement of said frames.

3. In a machine of the character described, a main frame supported adjacent an end thereof for tilting movement in a vertical plane, a main bowl pivotally supported adjacent the lower forward end thereof directly on said main frame and including a bottom wall, projecting means carried by said bowl, a secondary frame supported adjacent an end thereof for tilting movement in a vertical plane, the free end of said secondary frame being arranged relative to the free end of said main frame and pivotally connected thereto, operable control means for tilting said main and secondary frames for raising and lowering said bowl, and said secondary frame being also arranged and adapted to act upon said projecting means so as to swing said bowl about its pivotal mounting in a direction maintaining said bowl bottom in a substantially horizontal position during the tilting movement of said frames.

4. In a machine of the character described, a main frame supported adjacent an end thereof for tilting movement in a vertical plane, a main bowl pivotally supported on said main frame and including a bottom wall, journal means carried by said bowl, roller means carried by said journal means, a secondary frame supported adjacent an end thereof for tilting movement in a vertical plane, the free end of said secondary frame being arranged relative to the free end of said main frame and pivotally connected thereto, operable control means for tilting said main and secondary frames for raising and lowering said bowl, and said secondary frame being also arranged and adapted to act upon said roller means so as to swing said bowl about its pivotal mounting in a direction maintaining said bowl bottom in a substantially horizontal position during the tilting movement of said frames.

5. In a machine of the character described, a front frame supported adjacent the front end thereof for tilting movement in a vertical plane, a main bowl including a bottom wall, horizontal pivot means supported in fixed position on said main frame and by which said bowl is pivotally connected directly thereto for vertical tilting movement about said pivot means as an axis, a rear frame supported adjacent the rear end thereof for tilting movement in a vertical plane, the forward end of said rear frame being arranged relative to the rear end of said front frame and pivotally connected to said front frame, operable control means for tilting said front and rear frames for raising and lowering said bowl so as to selectively dispose the same in a loading or carrying position, and said rear frame being also arranged to act upon said bowl so as to swing the same about its pivotal mounting in a direction maintaining said bowl bottom in a substantially horizontal position during the tilting movement of said frames.

6. In a machine of the character described, a front frame supported adjacent the front end thereof for tilting movement in a vertical plane, a main bowl pivotally supported adjacent the lower forward end thereof directly on said front frame and including a bottom wall, projecting means carried by said bowl, a rear frame supported adjacent the rear end thereof for tilting movement in a vertical plane, the forward end of said rear frame being arranged relative to the rear end of said front frame and pivotally connected to said front frame, operable control means for tilting said front and rear frames for raising and lowering said bowl so as to selectively dispose the same in a loading or carrying position, and said rear frame being also arranged to act upon said bowl so as to swing the same about its pivotal mounting in a direction maintaining said bowl bottom in a substantially horizontal position during the tilting movement of said frames.

7. In a machine of the character described, a front frame supported adjacent the front end thereof for tilting movement in a vertical plane, a main bowl pivotally supported adjacent the lower forward end thereof directly on said front frame and including a bottom wall, projecting means carried by said bowl, a rear frame supported adjacent the rear end thereof for tilting movement in a vertical plane, the forward end of said rear frame being arranged relative to the rear end of said front frame and pivotally connected to said front frame, operable control means for tilting said front and rear frames for raising and lowering said bowl so as to selectively dispose the same in a loading or carrying position, and said rear frame being also arranged to act upon said bowl so as to swing the same about its pivotal mounting in a direction maintaining said bowl bottom in a substantially horizontal position during the tilting movement of said frames.

movement in a vertical plane, the forward end of said rear frame being arranged relative to the rear end of said front frame and pivotally connected to said front frame, operable control means for tilting said front and rear frames for raising and lowering said bowl so as to selectively dispose the same in a loading or carrying position, and said rear frame being also arranged to act upon said projecting means so as to swing said bowl about its pivotal mounting in a direction maintaining said bottom wall in a substantially horizontal position during the tilting movement of said frames.

7. In a machine of the character described, a front frame supported adjacent the front end thereof for tilting movement in a vertical plane, a main bowl pivotally supported on said front frame and including a bottom wall, journal means carried by said bowl, roller means carried by said journal means, a rear frame supported adjacent the rear end thereof for tilting movement in a vertical plane, the forward end of said rear frame being arranged relative to the rear end of said front frame and pivotally connected to said front frame, operable control means for tilting said front and rear frames for raising and lowering said bowl so as to selectively dispose the same in a loading or carrying position, and said rear frame being also arranged to act upon said roller means so as to swing said bowl about its pivotal mounting in a direction maintaining said bottom wall in a substantially horizontal position during the tilting movement of said frames.

8. In a machine of the character described, a rear frame supported adjacent the rear end thereof for tilting movement in a vertical plane, a main bowl pivotally supported adjacent the lower front end thereof directly on said rear frame and including a bottom wall, a front frame supported adjacent the front end thereof for tilting movement in a vertical plane, the rear end of said front frame being arranged relative to the front end of said rear frame and pivotally connected to said rear frame, operable control means for tilting said front and rear frame for raising and lowering said bowl so as to selectively dispose the same in a loading or carrying position, and operable means between said front frame and said bowl arranged to function in response to the tilting movement of said front frame so as to swing said bowl about its pivotal mounting in a direction maintaining said bowl bottom in a substantially horizontal position during the tilting movement of said frames.

9. In a machine of the character described, a rear frame supported adjacent the rear end thereof for tilting movement in a vertical plane, a main bowl including a bottom wall, horizontal pivot means supported in fixed position on said main frame and by which said bowl is pivotally connected directly thereto for vertical tilting movement about said pivot means as an axis, projecting means carried by said bowl, a front frame supported adjacent the front end thereof for tilting movement in vertical plane, the rear end of said front frame being arranged relative to the front end of said rear frame and pivotally connected to said rear frame, operable control means for tilting said front and rear frames for raising and lowering said bowl so as to selectively dispose the same in a loading or carrying position and link means between said front frame and said projection means arranged to function

in response to the tilting movement of said front frame so as to swing said bowl about its pivotal mounting in a direction maintaining said bottom wall in a substantially horizontal position during the tilting movement of said frames.

10. In a machine of the character described, a rear frame supported adjacent the rear end thereof for tilting movement in a vertical plane, a main bowl pivotally supported on said rear frame and including a bottom wall, journal means carried by said bowl, roller means carried by said journal means, a front frame supported adjacent the front end thereof for tilting movement in a vertical plane, the rear end of said front frame being arranged relative to the front end of said rear frame and pivotally connected to said rear frame, operable control means for tilting said front and rear frames for raising and lowering said bowl so as to selectively dispose the same in a loading or carrying position, and link means carried by said front frame and engaging said roller means so as to function in response to the swinging movement of said front frame for swinging said bowl about its pivotal mounting in a direction maintaining said bottom wall in a substantially horizontal position during the tilting movement of said frames.

11. In a machine of the character described, a main frame supported adjacent an end thereof for tilting movement in a vertical plane, a secondary frame supported adjacent an end thereof for tilting movement in a vertical plane, the free end of said secondary frame being arranged relative to the free end of said main frame and pivotally connected thereto so that both said frames may freely tilt upwardly and downwardly at their adjacent ends, a main bowl including a bottom wall, pivot means supported in fixed position on one of said frames and by which said bowl is pivotally connected directly thereto for tilting movement about a horizontal axis, operable control means for tilting said frames for raising and lowering said bowl so as to dispose the same in a loading or a carrying position, the other of said frames being arranged and adapted to act upon said bowl so as to tilt the same in a direction maintaining said bowl bottom in a substantially horizontal position during the tilting movement of said frames.

12. In a machine of the character described, a main frame supported adjacent an end thereof for tilting movement in a vertical plane, a secondary frame supported adjacent an end thereof for tilting movement in a vertical plane, the free end of said secondary frame being arranged relative to the free end of said main frame and pivotally connected thereto so that both said frames may freely tilt upwardly and downwardly at their adjacent ends, a main bowl including a bottom wall, pivot means supported in fixed position on one of said frames and by which said bowl is pivotally connected directly thereto for tilting movement about a horizontal axis, operable control means for tilting said frames for raising and lowering said bowl so as to selectively dispose the same in a loading or a carrying position, the other of said frames being arranged and adapted to act upon said bowl so as to tilt the same in a direction maintaining said bowl bottom in a substantially horizontal position in both loading and carrying positions of said bowl.

13. In a machine of the character described,

a rear frame, rear wheels supporting the same adjacent the rear end thereof for vertical tilting movement about said wheels as an axis, a front frame disposed forwardly of said rear frame and supported adjacent the forward end thereof for tilting movement in a vertical plane, the adjacent free ends of said frames being relatively arranged and pivotally connected so that both said frames may freely tilt upwardly and downwardly at their adjacent ends, a main bowl arranged forwardly of said rear wheels and including a bottom wall, pivot means supported in fixed position on one of said frames and by which said bowl is pivotally connected directly thereto for tilting movement about a horizontal axis, operable control means for tilting said frames for raising and lowering said bowl so as to dispose the same in a loading or a carrying position, the other of said frames being arranged and adapted to act upon said bowl so as to tilt the same in a direction maintaining said bowl bottom in a substantially horizontal position during the tilting movement of said frames.

14. In a machine of the character described, a rear frame, rear wheels supporting the same adjacent the rear end thereof for vertical tilting movement about said wheels as an axis, a front frame disposed forwardly of said rear frame and supported adjacent the forward end thereof for tilting movement in a vertical plane, the adjacent free ends of said frames being relatively arranged and pivotally connected so that both said frames may freely tilt upwardly and downwardly at their adjacent ends, a main bowl arranged forwardly of said rear wheels and including a bottom wall, means pivotally supporting said bowl adjacent the lower forward end thereof on one of said frames for vertical tilting movement about a horizontal axis, operable control means applied to said frames for tilting the same for raising and lower said bowl so as to selectively dispose said bowl in a loading or a carrying position, the other of said frames being arranged and adapted to act upon said bowl so as to tilt the same about its pivotal support in a direction maintaining said bowl bottom in a substantially horizontal position in both loading and carrying positions of said bowl.

15. In a machine of the character described, a rear frame, rear wheels supporting the same adjacent the rear end thereof for vertical tilting movement about said rear wheels as an axis, a front frame disposed forwardly of said rear frame and supported adjacent the forward end thereof for tilting movement in a vertical plane, the adjacent free ends of said frames being relatively arranged and pivotally connected so that both said frames may freely tilt upwardly and downwardly at their adjacent ends, a main bowl arranged forwardly of said rear wheels and including a bottom wall, pivot means supported in fixed position on one of said frames and by which said bowl is pivotally connected adjacent the lower forward end thereof directly to said one of said frames for tilting movement about a horizontal axis, operable control means for tilting said

frames for raising and lowering said bowl so as to selectively dispose the same in a loading or a carrying position, the other of said frames being arranged and adapted to act upon said bowl so as to tilt the same about its pivotal support in a direction maintaining said bowl bottom in a substantially horizontal position in both loading and carrying positions of said bowl.

16. In a machine of the character described, a rear frame, rear wheels supporting said rear frame adjacent the rear end thereof for vertical tilting movement about said rear wheels as an axis, a front frame disposed forwardly of said rear frame and supported adjacent the forward end thereof for tilting movement in a vertical plane, the free ends of said frames being relatively arranged and pivotally connected so that both said frames may freely tilt upwardly and downwardly at their adjacent ends, a main bowl pivotally supported adjacent the lower forward end thereof on one of said frames forwardly of said rear wheels so as to be raised and lowered therewith as said frames tilt to dispose said bowl in a loading or a carrying position, said bowl being operable to discharge material therefrom directly onto the ground, bowl adjusting means between the other of said frames and said bowl arranged to act upon said bowl so as to tilt the same in a direction maintaining said bowl in a substantially horizontal position in both loading and carrying positions of said bowl, said bowl adjusting means being adapted to permit free operation of said bowl to discharge materials exclusive of the tilting movement of said frames, frame control means for tilting said frames, and other control means applied to said bowl and adapted to operate exclusive of said frame control means to control the dischargings of said bowl.

17. In a machine of the character described, a rear frame, rear wheels supporting said frame adjacent the rear end thereof for vertical tilting movement about said wheels as an axis, a front frame disposed forwardly of said rear frame and supported adjacent the forward end thereof for tilting movement in a vertical plane, the adjacent free ends of said frames being relatively arranged and pivotally connected so that both said frames may freely tilt upwardly and downwardly at their adjacent ends, a main bottom arranged forwardly of said rear wheels, pivot means supported in fixed position on one of said frames and by which said bottom is pivotally connected adjacent an end thereof directly to said one of said frames for vertical tilting movement about said pivot means as an axis, operable control means for tilting said frames for raising and lowering said bowl so as to dispose the same in a loading or a carrying position, and means between the other of said frames and said bottom arranged and adapted to act upon said bottom so as to tilt the same in a direction maintaining said bottom in a substantially horizontal position in both loading and carrying positions of said bottom.

CHARLES LE BLEU.
